UNITED STATES PATENT OFFICE.

EDGAR L. GALE, OF BREMERTON, WASHINGTON.

DISPLAY APPARATUS.

1,424,350.

Specification of Letters Patent. Patented Aug. 1, 1922.

Application filed June 22, 1921. Serial No. 479,564.

To all whom it may concern:

Be it known that I, EDGAR L. GALE, a citizen of the United States of America, and resident of the city of Bremerton, in the 5 county of Kitsap and State of Washington, have invented certain new and useful Improvements in a Display Apparatus, of which the following is a specification.

My invention relates to display devices 10 and particularly to devices which are arranged to move a card or other article into position to be seen readily whereby its motion will attract attention, and then to return it to its original position and to move 15 another.

The object of my invention is to provide a simple, cheaply constructed and conveniently installed and operated apparatus for the purpose intended.

20 A further object is the provision of means, in such a selective moving apparatus, for varying the succession in which the articles are raised and for doing this conveniently and rapidly.

25 A further object is the provision of means which may be placed in an ordinary show window without mutilation thereof and which may be employed therein to operate selectively cards or articles of a number arranged in a single line, or to operate selectively a succession of such lines.

30 My invention comprises those novel parts and combinations thereof which are shown in the accompanying drawings, described in 35 the specification, and particularly defined by the claims terminating the same.

In the accompanying drawings I have shown my invention in the forms which are now preferred by me.

40 Figure 1 is a plan view of my present preferred form, a part being shown in section.

Figure 2 is an axial section through the operating or selecting mechanism therefor.

45 Figure 3 is an end elevation thereof.

Figure 4 is a perspective showing a detail of the operating mechanism.

Figure 5 is a plan view of a modified form.

50 Figure 6 is an end view thereof.

Figure 7 is a perspective of a detail of this form.

Figure 8 is a perspective showing the manner in which my device may be installed 55 and operated in a show window.

While my device may be employed in

connection with various articles to raise and to lower them so as to attract attention, it is particularly adapted to be used with cards such, for instance, as are employed in 60 real estate offices describing the various pieces of property listed for sale, and I shall, therefore, describe it only in connection with such cards. Ordinarily a window having only cards on display, containing pictures 65 or descriptions of the various pieces of property is a dead and uninteresting sight. By injecting movement into certain cards the attention of the passerby is attracted and his interest aroused, and thus it is that my 70 device is particularly adapted for such uses.

In general my device comprises two parts, 75 the motor with its attached actuating or selecting mechanisms, and the mechanism for supporting the cards and which is selectively actuated by the device driven by the motor. The motor 10 may be of any suitable type, preferably a spring motor. Secured upon a shaft 11 extending from the motor 10 are a series of selector disks 1. 80 These disks 1 are provided each with one or more selector members for contacting with other members to be later described and which are carried by the card holding members. 85

As shown in Figures 1-4 the selector members upon the disks 1 comprise cams 12. The preferred form of these cams contains a rise 16, a concentric still portion 15, and a drop 17. These cams may be formed integral with the disks 1 or separable therefrom. The disks may be made of wood and the cams provided with pins 13 which may be driven into the wooden disks to hold the cam thereon. These disks may be separated 90 slightly axially and I prefer that the relative positions of the various cams 12 be adjustable. I have shown the disks therefore, as having a central aperture 14. A sleeve 2, having a head 20 which engages the 100 side face of the cam at one end of the series, passes through the apertures 14 of all of the disks. These disks are secured thereon by means of a nut 21 threaded in the opposite end of the sleeve 2, and engaging the 105 side face of the disk at the opposite end of the series to that with which the head 20 contacts. By loosening the nut 21 the disks 1 may be adjusted angularly upon the sleeve 2 to vary the relative angular positions of 110 the cams 12.

The card holding members 30, which may

be of any suitable design, are secured upon tubes 3 to oscillate therewith. A number of tubes 3 are provided, each carrying its respective card holders at its outer end and 5 successively projecting at this end each from the preceding tube. The various tubes are thus nested one upon the other, or telescoped. At their inner ends they are connected to members which are contacted by 10 the cams 12 to oscillate each its respective tube 3. As shown in the preferred form each tube is connected to a lever 31 which is pivotally mounted between its ends each upon the next inner one of the series of 15 tubes 3, each lever being in position to be contacted only by its respective cam 12. A weight 32 may be mounted upon the opposite end of the lever to return it to normal position. The card holders 30 or the cards 20 C act as stops to limit this return movement, or other stops may conveniently be provided.

As the disks 1 carrying the cams 12 are rotated by the motor 10 the various levers 25 31 are oscillated each as its respective cam comes in contact therewith. This causes the tube 3 to which this particular lever 31 is connected to be oscillated to swing the card C upward into nearly vertical position before the observer. The cam 12 may be so arranged that its portion 15 will remain in contact with the lever 31 without causing further movement thereof, so that the card will be upheld motionless for a time. As 30 the drop portion 17 of the cam passes beyond the lever 31 the weight 32 causes this lever to fall back into normal position bringing the card again into horizontal position.

In the modification shown in Figures 5, 40 6, and 7 the disk 1 has formed on its periphery a series of gear teeth 18 terminating in a lug 19 having its periphery concentric with the disk. These disks as they rotate engage partial gears 35, which take the 45 place of the levers 31 and which are secured to the various tubes 3. The action is similar in all respects to that described above.

The card holders 30 may be formed in any manner found suitable or desirable. I have 50 shown them as formed of strips of somewhat resilient metal which are clamped about the tube 3 and held thereon by means of a screw and nut indicated by 36. In the form shown in Figure 3 the card C is provided with a flap C' and the card holder or 55 holders 30 is inserted between the flap and the card C. In the form shown in Figure 6 the card is held between the two ends of the card holder 30.

60 Such a device may be inserted in a show window by laying it upon the floor thereof and securing it lightly in place. It will operate to raise cards arranged in rows in any sequence in any row, to raise two or 65 more cards at a time, or it may be arranged

to operate all of the cards in each of several rows in succession. In Figure 8 the front row is shown with two cards thereof being simultaneously elevated. The two rear rows are connected to operate by a single 70 mechanism to be alternately elevated.

What I claim as my invention is:

1. A display device including a rotatable cam cylinder having axially spaced thereon a plurality of cams, levers each having an 75 arm positioned to be engaged by its respective cam, and a plurality of telescoped tubes each connecting at one end with its respective lever to be oscillated thereby, and having means at its opposite end for supporting 80 an article to be displayed.

2. A display device including a rotatable cylinder, a plurality of telescoped and relatively oscillable tubes each having means at one end for supporting an article to be displayed, and means for selectively oscillating 85 each of said tubes by engagement with the cylinder.

3. A display device including a plurality 90 of disks each having a contact member thereon, means for adjustably securing said disks to rotate together, a plurality of means each adapted to support an article to be displayed, and means operable from said contact members for selectively moving individual article supports.

4. A display device including a plurality 95 of disks each having a separable contact member secured thereon, means for connecting said disks to rotate together and permitting relative angular adjustment therebetween, a plurality of means each adapted to support an article to be displayed, and means operable from said contact members for selectively moving individual article 105 supports.

5. A display device including a plurality 110 of centrally-apertured disks each having a contact member thereon, a sleeve inserted in the apertures of said disks and having a head contacting with the face of one end disk, a bolt threaded in the opposite end of said sleeve and contacting with the face of the other end disk, whereby said disks may be relatively angularly adjusted, means for 115 supporting said sleeve and bolt for rotation of the disks, a plurality of means each adapted to support an article to be displayed, and means operable from said contact members for selectively moving individual article 120 supports.

6. A display device including a plurality 125 of telescoped and relatively oscillable tubes each having means at one end for supporting an article to be displayed, a lever secured to the opposite end of each tube, and means for selectively oscillating said levers.

7. A display device including a plurality 130 of telescoped and relatively oscillable tubes each having means at one end for support-

ing an article to be displayed, a lever secured to the opposite end of each tube, and means for selectively moving said levers from normal position, and for holding them 5 in the new position for a time before releasing them.

8. A display device including a plurality of telescoped and relatively oscillable tubes each having means at one end for supporting 10 an article to be displayed, a lever secured to the opposite end of each tube, and means for selectively moving said levers from normal position, and for holding them in the new position for a time before releasing

them, and means for insuring the return 15 of said levers to normal position.

9. A display device including a plurality of telescoped and relatively oscillable tubes each having means at one end for supporting an article to be displayed, a lever secured to the opposite end of each tube, and cams arranged to contact each with its respective lever to oscillate it, and to maintain it in the new position for a time before 20 releasing it.

Signed at Seattle, King County, Washington, this 17th day of June 1921.

EDGAR L. GALE.
